UNITED STATES PATENT OFFICE.

CHARLES Z. CELLER, OF NEW YORK, N. Y.

DRAWERS.

SPECIFICATION forming part of Letters Patent No. 288,012, dated November 6, 1883.

Application filed June 2, 1883. (No model.)

To all whom it may concern:

Be it known that I, CHARLES Z. CELLER, of the city, county, and State of New York, have invented certain new and useful Improvements 5 in Drawers, of which the following is a full, clear, and exact description.

Reference is to be had to the accompanying drawings, forming part of this specification, in which similar letters of reference indicate corresponding parts in all the figures.

Figure 1 is a front elevation of a pair of drawers illustrating my invention. Fig. 2 is a front elevation of the forward upper part of the right leg of the drawers. Fig. 3 is a front elevation of the forward upper part of the left leg of the drawers.

The object of this invention is to avoid heavy seams in the crotch and fly of drawers, and to strengthen the said crotch and fly against ripping.

The invention consists in drawers made with slots in the upper forward parts of their fronts, whereby the solid material of one front will form a seamless crotch and fly, and the solid material of the other front will form a seamless crotch and fly-facing, as will be hereinafter fully described.

A B represent the upper parts of the fronts of the right and left legs of a pair of drawers, 30 to which the waistband C is secured in the ordinary manner.

a b are strips formed by cutting slots D in the fronts A B, as shown in Figs. 2 and 3.

In making the drawers the strips a b of the fronts A B are placed upon the outer and inner sides, respectively, of the fronts B A, and are stitched to the said fronts, as shown in Fig. 1. With this construction there is no seam in the crotch and fly to rip or to inconvenience or chafe the wearer, and the drawers will be greatly strengthened in the place where they are most liable to give way.

Having thus described my invention, I claim as new and desire to secure by Letters Patent—

1. As an improved article of manufacture, drawers having each front made separately, and provided with strips a b, integral therewith, and secured, respectively, to the outer and inner sides of the fly-opening, and extending from the waistband to the crotch, as set forth.

2. In drawers, the fronts A B, having slots D formed in their upper forward parts, substantially as herein shown and described, whereby the solid material of one front will form a seamless crotch and fly, and the solid material of the other front will form a seamless crotch and fly-facing, as set forth.

CHARLES Z. CELLER.
